Inventor,
Ira Shoop,
By H. C. Scott & Co.
Attorneys,

UNITED STATES PATENT OFFICE.

IRA SHOOP, OF MANORVILLE, PENNSYLVANIA.

WRENCH.

SPECIFICATION forming part of Letters Patent No. 746,590, dated December 8, 1903.

Application filed April 8, 1903. Serial No. 151,586. (No model.)

To all whom it may concern:

Be it known that I, IRA SHOOP, a citizen of the United States of America, residing at Manorville, in the county of Armstrong and State of Pennsylvania, have invented certain new and useful Improvements in Wrenches, of which the following is a specification, reference being had therein to the accompanying drawings.

10 This invention relates to certain new and useful improvements in wrenches, the object of the invention being to construct a monkey-wrench with means whereby the movable jaw may be rapidly and easily adjusted whereby 15 to conform to the different sizes of nuts on which the wrench is to be employed.

Briefly described, the invention comprises, in connection with the wrench-shank carrying the rigid jaw at its outer end, a movable jaw 20 formed integral with the casing, which is slidably mounted on the wrench-shank and has its opposite side faces cut away, with the edges thereof dovetailed to receive the dovetailed edges of the side straps or arms of the 25 yoke which straddles the casing and has connected thereto a lock-block provided with teeth for engagement with the teeth of the wrench-shank. This lock-block is mounted in an opening provided therefor in the casing 30 and is normally held in engagement with the teeth of the wrench-shank by means of the spring connected to the back of the movable jaw, all of the above construction being hereinafter more fully described, and specifically 35 pointed out in the claims.

In describing the invention in detail reference is had to the accompanying drawings, forming a part of this specification, and wherein like numerals of reference indicate 40 like parts throughout the several views, in which—

Figure 1 is a side elevation of my improved wrench. Fig. 2 is a rear elevation thereof, partly broken away and partly in section. 45 Fig. 3 is a side elevation of the movable jaw in vertical section. Fig. 4 is a transverse vertical sectional view through the locking-yoke for the movable jaw. Fig. 5 is a detail perspective view of the movable jaw detached 50 from the wrench-shank. Fig. 6 is a detached detail perspective view of the locking-block.

In the accompanying drawings, 1 indicates

the wrench-shank provided at its inner end with a suitable handle 2 and at its outer end with a rigid jaw 3, said shank being provided 55 on its inner face with teeth 4. Mounted to slide upon this shank is a movable jaw 5, formed integral with the casing 6, which is provided with grooves 7 on its side faces near the rear end, the edges 8 of these grooves being dovetailed, as shown in Figs. 2 and 5. The casing 6 is cut away on its inner face to form a space 9, which receives the locking-block 10, the edges thereof being dovetailed to fit into dovetailed edges 11 of the cut-away 65 portion 9. This locking-block is provided with teeth 12, which project into the opening 14 in the casing and engage with teeth 4 of the wrench-shank. Operating in the dovetailed groove 7 of the casing are the side arms 70 or straps of the yoke 15, said arms or straps being secured rigidly by bolts or screws to the block 10. The block 10 is normally held in locked engagement by means of a spring 16, secured rigidly near one end to the back of 75 the movable jaw, as at 17, with its other end extending through in under the cross-bar of the yoke 15.

In using the wrench it is simply necessary 80 in order to permit the adjustment of the jaw 5 toward the handle to apply pressure, which may be readily done by the thumb on the cross-bar of the yoke 15, which will force the locking-block 10 away from the shank and allow the movable jaw to be slid toward the 85 handle 2. The adjustment of the movable jaw toward the rigid jaw may be accomplished by pressure against the rear end of the casing of the movable jaw, as the teeth 12 will readily slip over the teeth 4.

It is to be noted that the construction is extremely simple, there being no delicate parts to become disarranged, while the movable jaw is firmly held in its adjusted position. It will be further noted that various slight 95 changes may be made in the details of construction without departing from the general spirit of my invention.

Having fully described my invention, what I claim as new, and desire to secure by Letters 100 Patent, is—

1. In combination with a shank and fixed jaw thereof, a movable jaw mounted on said shank, said movable jaw being formed on its

sides with grooves and on its front face with a cut-out portion having its upper and lower walls recessed, a yoke encircling said movable jaw and being received in the grooves 5 thereof, a locking-block having dovetailed upper and lower faces mounted in the recesses of the cut-out portion of said movable jaw, said locking-block being secured to said yoke, and a spring secured to rear face of said 10 movable jaw and being bent outwardly therefrom and having its lower end engaging the inner face of said yoke.

2. In combination with a fixed jaw and the shank provided with a toothed face, a movable jaw having its sides formed with grooves 15 of dovetailed cross-sectional contour and its front wall formed with a cut-out portion having its upper and lower walls formed with re-

cesses, a yoke having its closed end normally out of engagement with the rear wall of said 20 movable jaw and its side arms mounted in the grooves of said jaw and being of similar cross-sectional contour, a toothed locking-block having dovetailed upper and lower ends mounted in said cut-out portion and being 25 secured to the forward ends of said yoke and a spring secured to said movable jaw and having its lower end bent outwardly therefrom and engaging the inner face of said yoke.

In testimony whereof I affix my signature 30 in the presence of two witnesses.

IRA SHOOP.
